SHEET SEVERING MECHANISM

Michael Maul, Berlin-Johannisthal, Germany, assignor to the firm Deutsche Hollerith Maschinen Gesellschaft m. b. H., Berlin-Lichterfelde, Germany

Substituted for abandoned application Serial No. 495,249, November 12, 1930. This application August 9, 1938, Serial No. 223,796. In Germany November 24, 1937

6 Claims. (Cl. 164—49)

This application is a re-file of application Serial No. 495,249, filed November 12, 1930.

The present invention relates to sheet severing mechanisms and more particularly to mechanisms for severing record sheets prepared in type printing apparatus.

In various kinds of type printing apparatus, the entries are made upon continuous record sheets which are severed into individual sheets or forms after the recording entries have been made thereupon and in order to permit easier handling of the sheets the record sheet may be wound upon a roll. As an example of machines of this kind, printing tabulating machines may be mentioned in which the accumulating and printing mechanisms are automatically controlled by perforated record cards and the printing mechanism may also be under the control of the accumulators for taking the totals. In such tabulating machines one line of data is printed during each of the successive cycles of machine operation upon a continuous record sheet which is automatically line spaced after each printing operation one step to feed the next blank line into printing position. In this way a continuous record sheet will be obtained having data printed in lines underneath each other. In almost all cases however, a number of lines of data belong to a certain group and the various groups are usually separated from each other by blank spaces to distinguish the groups and by severing the record sheet in accordance with said groups individual lists or forms may be obtained for each group of data. For instance, in a banking business statements of account are prepared in this way so that each customer receives a separate form containing the business transactions relating to the respective customer.

It is, therefore, the main object of the present invention to provide an improved mechanism for severing the record sheet preferably immediately adjacent to the printing mechanism.

A further object of the invention is to provide a severing knife in a type printing apparatus for severing a continuous record sheet immediately adjacent to said apparatus.

Another object of the invention is to provide closely adjacent to a platen roller for type printing apparatus a severing knife adapted to sever the record sheet which is fed by said roller.

Still another object of the invention is to provide a severing knife in a type printing apparatus, said knife being adjustable relatively to the printing line.

56 A further object is to provide a tensioning

mechanism for tensioning the record sheet before the severing operation takes place.

Further objects of the instant invention reside in any novel feature of construction or operation or novel combination of parts present in the embodiment of the invention described and shown in the accompanying drawings whether within or without the scope of the appended claims and irrespective of other specific statements as to the scope of the invention contained herein.

Though the present invention is particularly well adapted for the above mentioned automatically operated printing tabulating machines, its use is, by no means, limited to said machines but the mechanism may be used as well for various kinds of type printing apparatus in which similar requirements are set forth as in tabulating machines. The present invention is of particular advantage for such machines if comparatively wide record sheets are to be severed.

20 A preferred embodiment of the invention is shown in the accompanying drawings in which:

Fig. 1 shows a front view of the improved severing mechanism shown in connection with the printing platen or record sheet feed roller of a type printing apparatus such as, for instance, the printing mechanism of a tabulating machine;

Fig. 1a shows in side elevation the severing knife;

Fig. 2 is a section taken through the central portion of Fig. 1 and looking to the left side in Fig. 1;

Fig. 3 is an end view of the right side of the mechanism shown in Fig. 1;

Fig. 4 shows on an enlarged scale in side elevation a detail view illustrating the control of the interruptor contact for the current circuits of the magnets operating the severing mechanism;

Fig. 5 is an end view of the parts shown in Fig. 4;

Fig. 6 shows diagrammatically the normal relationship of the record sheet and the severing knife when the latter is at normal position;

Fig. 7 illustrates diagrammatically the position of the knife after the first severing phase;

Fig. 8 illustrates diagrammatically the position of the severing knife after the completion of the severing operation;

Fig. 9 is a detail view illustrating the control- 50 ling electro-magnetic mechanism for the tensioning frame;

Fig. 10 is the electrical wiring diagram.

The type box 11 of the type printing apparatus shown in Figs. 1 and 2 comprises a number of 55

adjacentely mounted type bars 12 each being provided with a plurality of type elements 13. The type bars are adjusted during each printing cycle to a certain position and when the type bars are 5 adjusted to printing position the type elements 13 at the printing line are simultaneously impelled towards the record sheet by means of hammers 14 so that a whole line is printed simultaneously. When the type bars 12 return to their 10 home position, the platen roller 15 will be rotated one step by means of a well known mechanism such as a pawl cooperating with a ratchet wheel 16 (Fig. 1) to shift the next blank line of the continuous record sheet 17 into printing position. The platen roller 15 is pivotally mounted by a shaft 18 journaled in the casings 19 and 20 and is provided with a hand wheel 21. The record sheet is unrolled from a supply roll 22 (Fig. 2) and is fed over the platen roller and over 15 guide bars, which will later be described, and the severed lists fall from a guide tray 23.

The severing mechanism, which shall now be described more in detail, is primarily carried by two side frame plates 24 and 25 which are carried by the shaft 18 and which are connected to each other. These connections comprise, in part, a holding roll 35 (Fig. 2), a guide bar and knife 28, and a guide bar 29 between which guide bars the record sheet is fed. The aforesaid roll 30 35 cooperates with a tightening or tensioning roll 36 to tension the record sheet before the severing operation.

The edge of a severing knife 37 (Figs. 1, 1a and 2) is inclined downwardly from the left to 35 the right so that the left edge of the severing knife is closest to the record sheet being fed between the bars 28 and 29, while the right hand end of the knife edge is further away from the record sheet. The knife 37 is provided with 40 a reinforcing projection bar 38 (Fig. 2) and carries on both rounded ends (Fig. 1a) pins 39 projecting into the slotted eyes 40 (see Fig. 1) of controlling plates 41 and 42. Each of the controlling plates 41 and 42 has two slots 43 (Fig. 2) 45 cooperating with pins carried by the frame plates 24 and 25 and serving to guide the plates on the frame plates 24 and 25, and a further pin 44 (Fig. 2) cooperating with the lower projection of each controlling plate serves as a stop.

50 Each controlling plate carries at its upper end a pin 45 (Fig. 2) projecting into the slot of a related lever 47, 48 and a lever 47, 48a, each pivotally mounted at 46. The arm 48 or 48a of said levers is provided with a pin projecting into a slot 49 of the armature plate 50. The armature plate 50 is guided by means of slots engaging pins 51 carried by the coordinated frame plate 24 or 25 and is normally held in the position shown in Figs. 2 or 3, since a spring 52 tends to draw the related arm 47, 48, 47, 48a in a counterclockwise direction (Fig. 2). The ends of the guide bars 28 and 29 (Fig. 1) are shouldered and are fastened to the frame plates 24 and 25. The 55 knife edge of the knife 37 is normally below the knife edge of the guide bar 28 so that the paper 17 may be unobstructedly fed between said knife edges. The knife 37 is provided on both ends with projections 53 (Figs. 1 and 1a). Two springs 54 60 serve to draw the knife with its stops 53 against the knife edge of the guide bar 28 so that upon its raising movement the knife 37 is always in close contact with the knife edge of the guide bar 28.

In order to raise the knife for the severing operation, the controlling magnets 55 and 56 are

sequentially energized. Upon energization of the controlling magnet 55, the coordinated armature plate 50 is drawn downwardly thereby acting upon the pin fastened to the arm 48a (Fig. 2) and pressing the latter downwardly, the pin of the arm 48a then moving in the slot of the armature plate 50 about the pivot 46. Consequently, by means of the pin 45 the controlling plate 41 and also the knife 37, which is connected thereto by means of the pins 39 projecting into the slots 10 of eyes 40, will be drawn upwardly at the left end (Fig. 1) and the sheet will be severed from its left edge to the middle portion. At the end of the first severing phase the knife is in the position shown diagrammatically in Fig. 7. In a 15 manner still to be described, the magnet 56 (Fig. 1) will then be automatically energized and at the right side of the severing mechanism the same operations will take place as have taken place at the left side so that now the right side 20 of the knife will be drawn upwardly; thereby the severing line between the knife bar 28 and the knife 37 will run from the middle portion to the right hand edge of the record sheet. At the end of the second severing phase the knife is in 25 the position shown diagrammatically in Fig. 8.

For tensioning or tightening the record sheet before the severing operation takes place, the following described mechanism is preferably provided:

The above mentioned tensioning or tightening roll 36 (Figs. 1 and 2) is carried by two side arms 57 which are pivotally mounted at 58 to the frame plates 24 and 25. Each of the arms 57 carries a contact arm 59 and a latch extension 60. Each latch extension 60 is normally in the position shown in Fig. 2 in dotted lines and is normally in engagement with a latch 61 which is drawn by a spring 62 against a stop thus holding the roll 36 in latched position. The latch 61, in turn, 40 is pivotally connected to a bell crank lever 63 pivoted at 63' and the other arm of said bell crank lever is connected by a pin and slot connection with the lower projection of the related controlling plate 41 or 42. Each of the latches 61 has a projection 64 (see also Fig. 9) extending through the coordinated frame plate to the outside and forming the armature of a magnet 65. On each of the frame plates 24 and 25 the related magnet 65 is fastened by means of an 50 angle piece 66 (Fig. 1). The springs 67 (Fig. 2), arranged on both sides and cooperating with the arms 59, tend to rock the tensioning roll frame normally in counterclockwise direction, said rocking, however, being prevented by the aforesaid 55 latch mechanism. During the regular printing operations the record sheet is fed by means of the platen roller 15 step by step between the guide bars 28 and 29 preferably with the aid of small feed rollers (not shown) provided at the sides of the frame plates and driven in unison with the platen roller 15 while the paper is fed over the roller 35. Since the record sheet has a certain rigidity, the leading edge will not drop down to the tray 23 immediately after leaving the bar 65 29 but it will be advanced in a horizontal or even in an upwardly inclined direction over the roll 35 but beneath the roll 36 which is positioned normally as shown in dotted lines. If a severing operation is then initiated the magnets 65 will 70 first be simultaneously energized. Thereby the latches 61 are disengaged from the extensions 60 and the springs 67 will rock the arms 57 and the tensioning roll 36 in a counterclockwise direction (Fig. 2) to engage with the stationary 75

roll 35 and thereby the record sheet 17 held between rolls 35-36 will be tensioned between the bar 29 and the rolls 35 and 36. For the actual severing operation the magnet 55 is then energized so that the knife 37 is raised and the paper sheet will be pressed against the knife edge of the guide bar 28, and the cut will be executed in the above described manner from the left to the right (Fig. 1). Upon the energization of magnet 55 and the subsequent elevation of the controlling plate 41, the bell crank lever 63 will be rocked in a counterclockwise direction and the latch 61 at the left side will be moved towards the extension 60 far enough to catch under the extension 60. As will be seen from the specification following, the magnet 55 will now remain energized and will cause the energization of magnet 56 and the second severing phase. Then the latch 61 at the right side (Fig. 20) will be moved towards and catch under the extension 60 so that at the end of the severing operation both extensions 60 will be caught by the latches 61 but the tensioning roll frame will remain in tensioning position. If now the current circuit for magnets 55 and 56 is interrupted, and the springs 52 return the knife 37, and the controlling plates 41, 42 to home position, each bell crank lever 63 will be rocked in counterclockwise direction (Fig. 2) to its normal position and 25 since the latches 61 are in engagement with the extensions 60, the tensioning roll frame will be rocked in clockwise direction and the roll 36 will again be moved to the position shown in dotted lines. During the subsequent printing operations the paper is then permitted to be fed freely between the separated rolls 35 and 36.

The contact controlling mechanism serving for the control of the proper timing of the subsequent operations will now be explained.

40 As may be seen from Fig. 2, there are provided two contacts 70 and 71' at the left side of the severing mechanism. The contact 70 is normally open and is closed when the magnet 55 is energized at the end of the first severing phase. The contact 71' is also normally open and is closed when the tensioning roll 36 is in close contact with the roll 35. The parts are shown in the drawings in the position which they are in after the unlatching of the tensioning roll frame but before the first severing phase. At the right side of the severing mechanism there is a contact 71'' (Fig. 3) and in a similar manner this contact is under the control of the right hand arm 59 of the tensioning roll frame.

55 The arm 48 controls a contact 75 only at the right side of the severing mechanism and the arrangement at the right side is shown clearly in Figs. 5 and 4. To more clearly illustrate the parts in Fig. 4, it is assumed that a part of the frame plate 25 has been broken away. The arm 48 at the right side has a groove 72 adapted to receive a pin 73 of a controlling plate 74 for the contact 75. The contact plate 74 is guided by means of pins 76 on the frame plate 25 and the normal position of the plate 74 is effected by a spring 78 moving the plate 74 towards the left so that the pin 73 is in engagement with the lower end of arm 48. The contact 75 is carried by the frame plate 25 and the contact 75 is received by a recess 77 of the controlling plates 74 and in such a way that the left edge of recess 77 keeps the contact 75 normally closed.

60 On the arm 48 is pivoted a pawl 79 engaging by means of a sidewardly projecting lug 80 the lower portion of the groove 72. The pawl 79 is pivoted by a rod 81 carried by the plate 48 and to the rod 81 there is attached an arm 82 tending by means of a spring 83 to draw pawl 79 normally in clockwise direction (Fig. 4) so that the lug 80 closes the lower portion of groove 72. When the arm 48 is drawn downwardly by the energization of the magnet 56, the pin 73 rides along the outer edge of pawl 79 and the contact 75 will remain closed. When, however, the arm 48 reaches its lowermost position and, therefore, the second phase of the severing operation has been completed, the pin 73 is just above the pawl 79 and is opposite the upper entrance of groove 72 so that the spring 78 will now draw the plate 74 to the left. The pin 73 now rides in the upper portion of groove 72 to the left and the contact 75 opens.

65 Upon the return of the parts to their normal position, the arm 48 is drawn upwardly and the pin 73 will not now ride along the outer edge of the pawl 79 but will ride down between the wall of the groove 72 and the inner edge of pawl 79 and the pin 73 will ultimately rock the pawl 79 to the right (Fig. 4), and will ride out of said groove and underneath said lug 80. The pin 73 and the controlling plate 74 now reach the position shown in Fig. 4 and the contact 75 will again be closed and the lug 80 will again close the lower entrance of groove 72. Upon another severing operation the lug 80 will prevent the pin from passing upwardly through the groove 72 so that the pin 73 is forced to ride along the outer edge of pawl 79.

70 The aforesaid provision has been made to secure on the one hand that the deenergization of the current circuits is positively effected only when the severing of the record sheet has been effectively and completely taken place and, on the other hand, that the contact 75 controlling the interruption of the current circuits may not be closed again before the return to home position of all parts is completed, in order to prevent any accidental simultaneous closure of contact 75 and contacts 71, 71' and 71''.

75 Fig. 10 shows the electrical diagram of the severing mechanism. The current source 85 is in series with the contact 75 controlling the disconnection of the magnets from the current source. The latch magnets 65 are shunted across the lines 87, 88 by means of a contact 86 which in turn is controlled by a release key 89. The controlling magnet 55 is connected to the lines 81, 88 by the contacts 71' and 71'' and the controlling magnet 56 of the right side is connected to the lines 86, 87 by the contact 10. The contact 75 is controlled in the above described manner by the controlling plate 74 and is normally closed.

80 The operation of the mechanism will now be briefly described in connection with the electrical circuit diagram. After a certain number of printing operations and step by step feeding movements of the record sheet, the severing of the printed part of the sheet may be effected by the operator when he presses the key 89 thereby closing the contact 86. If the mechanism is to be controlled automatically, a contact 90 may be provided for this purpose, said contact being under the control of a suitable element of the machine. By closing one of said contacts 86 or 90, the two magnets 65 will be energized and the latches 61 (Fig. 2) are attracted so that the springs 67 are permitted to rock the tensioning roll frame in a counterclockwise direction and the rolls 35, 36 will now tension the record sheet.

When the roll frame is in this position both contacts 71' and 71'' will be closed and since said contacts are arranged in series with the magnet 55, they will effect the energization of the controlling magnet 55 only when the tensioning roll frame is completely in tensioning position at both ends. By the energization of magnet 55 the left end of the knife 37 will be drawn upwardly and the severing of the record sheet will be effected from the one edge to the middle portion (Fig. 7). Since the tensioning roll frame remains in tensioning position, the contacts 71' and 71'' will also remain closed and consequently the magnet 55 will remain energized. However, at the end of the first severing phase, the contact 70 (Fig. 2) will be closed by the arm 48a at the left side and, therefore, subsequent to the first severing phase the magnet 56 of the right side will be immediately energized and the knife will also be drawn upwardly at the right side to complete the severing operation (Fig. 8). At the end of this second severing phase, however, due to the above described movement of the controlling plate 74 (Fig. 4) to the left, the contact 75 will open and thereby the current supply will be interrupted to the magnets 65 as well as to the magnets 55 and 56 (see also Fig. 10) so that all parts will now return to their normal position (Fig. 2) and also the tensioning mechanism will return to its rest position. The contact 75 will, at the end of these operations, again be closed by means of the controlling plate 74. At the end of the severing operation all parts are in proper position ready for another severing operation.

The whole severing mechanism may be adjusted relatively to the printing line so that the cutting line is adjustable relatively to the printing line. For this purpose the plate 24 (Fig. 1) is not pivoted upon the platen shaft 18 but upon a sleeve 50' fastened to the casing 19 in which the shaft 18 is journaled. At the threaded left end of sleeve 50' is a hand wheel 51' provided to clamp the side plate 24 against the casing 19 so that the whole severing mechanism may be adjusted to a certain position. If the cutting line is to be changed relatively to the printing line the hand wheel 51' must be loosened and the side plates 24, 25 with the bars 28, 29 as well as the knife, magnets and tensioning roll mechanism will be rocked about the shaft 18 (see Figs. 1 and 2) and again fastened in the desired position by screwing the hand wheel 51' against the plate 24. If it is desired to sever the sheet immediately behind the last printing line, the severing frame is rocked to the left as far as possible (Fig. 2). But if a certain blank space is to remain after the last printing line, the severing mechanism will be adjusted accordingly and an additional feed must be imparted to the record sheet before severing may take place.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a sheet severing mechanism for a printing apparatus for severing continuous sheets fed by a platen roller comprising a fixed knife blade, a movable knife blade, means for supporting said knife blades to mount the latter longitudinally above said platen roller, and means for elevating said movable knife blade radially with relation to said platen roller away from the periphery of said platen roller and against said fixed knife blade to sever said sheet close to the periphery of 10 the platen roller.

2. A sheet severing mechanism for a printing apparatus for severing continuous sheets fed by a pivoted platen roller comprising a fixed knife blade, a movable knife blade, means pivoted centrally with said platen to support said blades longitudinally above said platen roller, means for effecting a relative movement of said blades to sever said sheet close to said platen roller, and means for effecting various adjustments of said 20 supporting means to position said blades at a desired distance from a fixed printing line of said platen roller.

3. A sheet severing mechanism for a printing apparatus for severing continuous sheets fed by a platen roller comprising a fixed knife blade, a movable knife blade, means for supporting said knife blades to mount said blades longitudinally above said platen roller, a plurality of operating means each having a pivotal connection to opposite ends of said movable knife blade, means for actuating one of said operating means about the pivotal connection with said other operating means to move said movable blade against said fixed blade to partially sever said sheet, and 35 means for then actuating said other operating means about the pivotal connection of the operating means first operated to thus completely sever said sheet.

4. A sheet severing mechanism comprising a 40 fixed knife blade, a movable knife blade, a plurality of knife blade operating means each having a pivotal connection to opposite ends of said movable knife blade, and a plurality of sequentially energized electromagnets, each actuating the related operating means to rock said movable knife blade against said fixed knife blade about the pivotal connection with the other operating means to thereby sever said record sheet in two operations of said movable knife blade.

5. A sheet severing mechanism for severing a continuous sheet fed by a platen roller, a fixed knife blade, a movable knife blade, means for mounting said blades longitudinally above said platen roller, means for guiding said sheet between and through said knife blades to enable the leading edge to be unsupported, and means for engaging the leading edge of said sheet and to place said sheet in tension prior to a severing operation by said movable blade.

6. In a type printing apparatus provided with a platen roller, a severing mechanism comprising a fixed blade and a movable severing blade, means for placing a record sheet in tension between the platen roller and the leading edge of the sheet, 65 and means for adjustably carrying the aforesaid means whereby said severing mechanism may be adjusted to effect a severing of the sheet at desired distances of the printing line of said platen roller.

MICHAEL MAUL.
